FOOD BROILER

Thomas C. Payne, Rte. 1, Rockton, Ill.

Filed May 15, 1964, Ser. No. 80,003

Term of patent 14 years

(Cl. D81—10)

I claim:

The ornamental design for a food broiler, substantially as shown.
